UNITED STATES PATENT OFFICE.

WILLIAM A. HUNT, OF WEST LEBANON, INDIANA, ASSIGNOR, BY MESNE ASSIGNMENTS,
TO FRANK N. PENCE, OF PENCE, INDIANA.

WAGON-RACK.

1,285,193.

Specification of Letters Patent. Patented Nov. 19, 1918.

Application filed January 22, 1914. Serial No. 813,728.

To all whom it may concern:

Be it known that I, WILLIAM A. HUNT, a citizen of the United States, residing at West Lebanon, in the county of Warren and State of Indiana, have invented a new and useful Wagon-Rack, of which the following is a specification.

This invention relates to wagon racks and more particularly to racks for use in transporting live stock.

One of the objects of the invention is to provide a rack of this character made up of angle strips and which is adapted to be quickly placed in or removed from position upon the floor of an ordinary wagon rack, the various parts of the rack being held together and to the floor by means of bolts, certain of which also constitute pintles upon which are mounted the end gates or doors of the rack.

A further object is to provide a rack of this character which can be quickly collapsed and which can be stored in a small space.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:

Figure 1 is a perspective view of the rack, the same being shown set up in position upon the floor of an ordinary wagon rack.

Fig. 2 is an enlarged vertical transverse section through a portion of the rack taken on the line 2—2 Fig. 1.

Fig. 3 is a section on line 3—3 Fig. 1.

Fig. 4 is a section on line 4—4 Fig. 1.

Referring to the figures by characters of reference 1 designates the floor of an ordinary wagon rack, the same being adapted to support the structure constituting the principal part of the present invention. This structure includes corner standards 2 made up of angle strips, these standards being connected by top angle strips 3 which bear downwardly thereon and lap the outer sides thereof and by bottom angle strips 4 which

are secured upon the sides of the standards and bear downwardly upon the floor 1. Intermediate angle strips 5 connect the standards 2 so that side panels are thus produced by the standards and the various angle strips connecting them. Intermediate vertical angle strips 6 are secured to the inner sides of the strips 3, 4 and 5.

Extending through the ends of one of the top strips 3 are bolts 7. These bolts are arranged longitudinally back of and close to the adjacent standards 2 and are extended through the floor 1 so that, by tightening the bolts, one of the side panels will be fastened securely upon the floor. Brackets 8 are fixedly connected to by bolts or rivets 81 and extend inwardly from the ends of the other top strip 3 and a bolt 9 is extended downwardly through each of these brackets and close to the adjacent standard 2 and through the floor 1. Thus by tightening these bolts 9, the panel adjacent thereto will be fastened securely to the floor. Mounted to swing upon each of the bolts 9 is a gate 10 formed of top and bottom angle strips and of intermediate and side strips, all suitably connected to form a rigid structure. Each gate is adapted to close the space between the side panels at one end and any suitable form of latch such as indicated generally at 11, may be provided for fastening each gate in closed position.

For the purpose of preventing the side panels from buckling outwardly when pushed against by the stock held within the rack, plates 12 may be secured to the inner side of each of the lower side strips 4. Each of these plates has a finger 13 extending downwardly therefrom and adapted to project through an opening 14 in the floor 1. Thus it will be seen that buckling of the side panels when pushed against by the stock, is prevented.

It will be noted that the panels are not connected together at their upper ends and, consequently, when the gates are open, there is nothing extending across the rack which would interfere with the admission of stock to or the removal of stock from the rack. The gates, when closed, constitute ample means for connecting the side panels.

It will be seen that simply by removing the bolts 7 and 9 and disengaging the gates from bolts 9, the entire rack can be quickly collapsed and stored in a small space. Thus the floor of one of the racks can be used for

other purposes in connection with the running gear of a wagon.

What is claimed is:—

1. The combination with a rack floor, of 5 side panels, fingers depending from the side panels and projecting into the floor to hold said panels perpendicular to the floor, bolts extending throughout the height of the end portions of the panels and through the floor 10 for binding the panels upon the floor, gates pivotally mounted upon the bolts of one of the panels, and means upon the gates co-operating with the opposed panel for holding the gates closed and for tying the panels 15 together.
2. The combination with a rack floor, of side panels, fingers depending from the side panels and projecting into the floor to hold said panels perpendicular to the floor, bolts 20 extending throughout the height of the end portions of the panels and through the floor for binding the panels upon the floor, each panel including a bottom angle strip bearing downwardly upon the floor, gates carried by the bolts of one of the panels, and 25 co-operating means upon the gates and the opposed panel for securing the gates in closed position and for tying the panels together.
3. The combination with a flat topped rack floor, of rack side panels, fastening means extending throughout the height of the end portions of the panels and into the floor for binding the panels in vertical position upon the floor, gates pivotally mounted 35 upon the fastening means for one of the panels, and means for detachably fastening the other sides of the gates to the corresponding ends of the other panel.
4. The combination with a flat topped 40 floor, of rack side panels, bolts extending throughout the end portions of the panels and into the floor for binding the panels

upon the floor in vertical positions, gates pivotally mounted on the fastening means 45 for one of the panels, and means for detachably fastening the other sides of the gates to the corresponding ends of the other side panel whereby the gate when closed and fastened will tie the adjacent ends of the 50 panels together.

5. The combination with a flat topped rack floor, of rack side panels, fastening means extending into the floor for binding the panels in vertical position upon the 55 floor, gates pivotally mounted upon the fastening means for one of the panels, and means for detachably fastening the other sides of the gates to the other panel whereby the gates when closed and fastened will tie 60 the opposing ends of the panels together.

6. A rack for hauling live stock, comprising a flat rack floor for a wagon, rack side panels, bolts extending throughout the height of the end portions of said panels for 65 binding the panels upon the floor and in a vertical position, fingers depending from the side panels intermediate the ends of the panels, said fingers fitting tightly into holes 70 in the floor whereby the fingers assist in holding the panels in vertical position and prevent lateral movement of the intermediate portions of the panels, gates swung on the bolts for one of the side panels, and means carried by the gates and co-operating 75 with the other panel to fasten the gates when closed and thereby tie the side panels together.

In testimony that I claim the foregoing 80 as my own I have hereunto affixed my signature in the presence of two witnesses.

WILLIAM A. HUNT.
